UNITED STATES PATENT OFFICE.

JOHN SJUNNE SELANDER, OF NEW YORK, N. Y.

DRILL-CASE.

1,192,575.

Specification of Letters Patent. Patented July 25, 1916.

Application filed February 2, 1916. Serial No. 75,783.

To all whom it may concern:

Be it known that I, JOHN SJUNNE SELANDER, a subject of Gustavus V, King of Sweden, and resident of 266 Wyckoff street, in the borough of Brooklyn, county of Kings, city and State of New York, have invented certain new and useful Improvements in Drill-Cases, of which the following is a specification.

10 This invention relates to drill cases or containers and especially to that class where a whole range of sizes of drills are contained in one case.

15 It is one advantage of this invention to provide a drill box with two lids permitting access to any inclosed drill without disturbing the rest.

20 Another advantage is to provide a case which, when open, will serve as a display stand for a set of drills.

Another advantage is to provide a case which is adapted to receive a collapsible drill stand.

25 Another advantage is to provide a case for drills which, when closed, entirely prevents any drill from being dislodged.

Further advantages and possibilities will become apparent as the specification proceeds.

30 With the aforesaid advantages in view, the invention comprises the improvements and combinations of parts hereinafter described in their embodiment, pointed out in the claims and illustrated in the accompanying drawing, which shows this set of improvements.

In the drawing: Figure 1 is a perspective view of a case including this invention. Fig. 2 is a perspective view of a collapsible drill stand. Fig. 3 is a side view of the case of Fig. 1 with one lid open and including the stand of Fig. 2 and indicating the positions of drills by dotted lines. Fig. 4 is another view of the other side of Fig. 3, with the other lid open. Fig. 5 is a sectional view of Fig. 3 when both lids are normally open and the drill stand in position. Fig. 6 is similar to Fig. 5, the drill stand being partly folded together and the case being ready for closing.

The same numerals indicate the same parts throughout the figures.

It is often very annoying and a source of great trouble for mechanics to find that their drills have been disarranged and mixed up and sometimes broken when they have had

occasion to open their drill boxes to take out a particular drill. Especially true has this been when a drill stand has been taken anywhere inside a satchel or a case filled with a set of drills. On the other hand, many times it has been found entirely impractical to take a whole set of drills out to a job despite the undoubtedly convenience of having as many sizes of drills as possible, owing to the counteracting difficulty of having the drills disarranged and possibly lost, entailing a loss of time in hunting and rearranging dislodged drills.

It has been sought to introduce into this invention special provisions against possible dislodgment or loss of any drills carried within the same.

Referring to the drawings, the case comprises the parts as follows: The bottom 12, top 4, back 7 and the front 3, as well as lids 1 and 2, the latter being hinged to back 7 by hinges 24 and 23 as in Figs. 5 and 6. On the lids are screws 14 and 15 which in combination with hook 16 form closures for the case. On the bottom 12 are secured a pair of longitudinal blocks 13 and 11 against the back 7 in such manner as to provide a slot 10. On the lids are secured angle plates 17 and 18 which contain the slots 8 and 9. A pair of drill abutments are also shown as 5 and 6.

In Fig. 2 is shown a drill stand which is collapsible by virtue of the three interfolding parts 20, 21 and 22, the pegs at the corners noted as 8', 9' and 10' being adapted to fit in slots 8, 9, and 10, respectively, of the case as shown in all other figures, especially Figs. 5 and 6.

When the stand is to be set into the case, the parts are opened considerably so that parts 20 and 22 which normally meet at the corner above peg 9' are as far apart as possible. Then part 22 is passed in toward the right under abutments 5, 6 and 19, and pegs 9' and 10' slipped into slots 9 and 10. Then the remaining peg 8' is set into slot 8 and part 20 set to meet part 22 at the joint above peg 9', resulting in a position illustrated in Fig. 5. It will be noted that the drills will fit in the drill stand in the following order as shown in Figs. 3, 4, 5 and 6. Part 20 holds the small range of drills 25; part 21 holds the medium drills 26, and part 22 holds the large drills 27.

When the stand with the drills is in position in the case as described and as shown in

Fig. 5, and it is desired to close the case, part 20 is folded up to part 21 as shown in Figs. 3 and 6. Lid 2 is then closed as shown in Fig. 4, the large drills 27 in part 22 setting in beneath the drill abutment 5, the latter being also visible in Figs. 1 and 3. Then lid 1 is closed, resulting in a position shown in Fig. 3, the drills 25 in part 20 fitting and setting in beneath abutment 6, and drills 26 in part 21 setting in under abutment 19, further shown in Fig. 4. Finally the devices denoted by 16 are hooked to the screws 15 and 14, etc., on lids 1 and 2 and the case is entirely closed. It is perfectly obvious that as the pegs 8', 9', and 10' are in the slots 8, 9 and 10, the drills 25, 26 and 27 being in the stand parts 20, 21 and 22 and abutting drill abutments or retainers 5, 6 and 19, then no drill can in any way be dislodged or even moved longitudinally nor can the parts 20, 21 and 22 be dislodged while lids 1 and 2 are in closed position.

Having thus fully described my invention, what I claim as new and desire to obtain by Letters Patent is:

1. A drill case comprising four joined members having each a pair of free edges, a pair of oppositely hinged lids secured to the two free edges of one of said members, and means upon the inner surfaces of said lids and within said case for supporting a drill stand, said means comprising cleats or plates containing slots or orifices, substantially as described.

2. A drill case including four joined sides constituting a front, a back, a top and a bottom, respectively a pair of lids being attached to the free edges of said back, said lids being hinged and adapted to swing away from each other when opened; a pair of cleats spaced apart to provide an intermediate slot being secured to said bottom parallel with the free edges of the same and abutting the back; a plate or extended block located on the inner side of each of said lids in a position near the free end of the same and near the bottom and parallel with the latter; a longitudinal slot in the upper horizontal surface in each of said longitudinal blocks or plates, said slot and aforesaid in-

termediate slot being adapted to receive the pegs or feet of an interlocking collapsible drill stand, substantially as described.

3. A drill case including a casing having a back, a front, a top and a bottom joined together, and a pair of lids hinged to said back means located on said bottom and upon said lids for receiving and seating a detachable drill stand and means within said top for retaining drills in position, said latter means comprising parallel longitudinal cleats secured to and within said top to provide drill abutments, substantially as described.

4. In a drill case, in combination, a rectangular casing having hinged lids attached thereto and means within said casing and on said lids for receiving and seating an interlocking or collapsible drill stand, with means secured in said casing for retaining in position drills in said stand when in collapsed or folded position, said means comprising longitudinal drill abutments within the top of said case, said abutments having several different oblique edges adapted to abut and retain drills, substantially as described.

5. A drill case including four sides, comprising a top, bottom, front and back, said back and bottom being joined; means for seating a drill stand in said case comprising a slot in an addition to said bottom, said slot abutting said back and being substantially parallel with said bottom; a pair of doors or lids being hinged to said back, additional means for seating said drill stand being located on the inner surfaces of said lids in the form of plates with longitudinal slots therein, said slots being parallel with said inner surfaces of said lids and lying in substantially the same plane as aforesaid slot within said case, substantially as described.

Signed at 132 Nassau street, in the borough of Manhattan, county of New York, city and State of New York, this 29th day of January, A. D. 1916.

JOHN SJUNNE SELANDER.
